UNITED STATES PATENT OFFICE.

FRANZ BREITSCHEID, OF ST. LOUIS, MISSOURI.

TRUSS.

SPECIFICATION forming part of Letters Patent No. 309,518, dated December 23, 1884.

Application filed July 28, 1884. (No model.)

To all whom it may concern:

Be it known that I, FRANZ BREITSCHEID, a subject of Prussia, residing at St. Louis, in the State of Missouri, have invented a new and useful Improved Hernia-Truss, of which the following is a specification.

The objects which my improvements have in view are to cause the pressure of the pad to be in the natural direction against the hernia-sack—that is to say, in an axis parallel to the inguinal canal; also to be capable of increasing or diminishing the said pressure to suit the requirements of the patient; to be capable of adjusting the pad; also adjusting the parts connecting same to the end of the steel band, and otherwise to achieve the advantages of enabling the truss to conform to the bodily wants of the wearer and produce a most speedy and reliable cure for hernia. I attain these objects by the mechanism illustrated in the accompanying drawings, in which—

Figure 1 is a perspective view of my improved hernia-truss as it appears when ready to be applied and used. Fig. 2 is an enlarged front view of the pad and its connections to the end of the steel band, said figure being also designed to show more clearly the intermediate mechanism between the said pad and the band. Fig. 3 is a part plan and plan section of the same parts shown in Fig. 2. Fig. 4 shows in detail view the shape of the spring used. Fig. 5 shows the pivotal stem. Fig. 6 shows the face-plate. Fig. 7 shows the engagement by its pin of the pivotal stem in the end of the steel band, and Fig. 8 is a detail view of the end of the steel band when looked at from the outside.

Similar letters refer to similar parts throughout the several views.

40 A represents the steel or metal band, and B the leather strap usually used to strap the truss to the body.

C represents the pad, forming part of which is the socket-plate e, in the socket of which the screw c' engages that pivots the pad-plate D and pad C together. The plate D has one or more holes, d, to secure the pad, and so that same can be located to suit the wearer, (see Figs. 1, 2;) also, the pad-plate D has, further, 45 one or more studs or buttons at d' d'', (see Figs. 1, 2, 3,) to which the leather strap can be fastened in any of its holes. When the strap is

fastened to the lower button, the pressure of the pad will be more decisively in an upward direction, and when fastened to the upper button the pad pressure is more horizontal or parallel with the body of the wearer. 55

E is a sleeve or tubular end forming part of the pad-plate D. (See Figs. 2, 3.) In this sleeve the end of the pivotal stem F engages as will hereinafter appear, and on the outside the said sleeve has screw-threads e, to which the end of the spiral spring can be secured. (See Figs. 2, 3.)

By referring to Figs. 3, 5, 7, the pivotal stem F is shown as consisting of the stem portion f, which at f' is screw-threaded, and at f'' has a face-shank.

G is the spiral spring. One end of this spring is secured to the threaded end of the sleeve E, 70 and the other end of the spring is secured or screwed on the threads f' of the pivotal stem F, as shown in Figs. 2, 3. The pivotal stem F is therefore arranged to pass inside the spring, its stem f having free play inside the sleeve E, while by its shank f'' said stem is adapted to connect all said parts to the end of the metal band, as indicated. By thus connecting the pad by its pad-plate to the end of the spiral spring, and connecting the remaining end of said spring to the pivotal stem, which in turn is secured rigid to the metal band, the tension of said spring is most advantageously adapted to impart mechanical pressure to the pad. The pad can be sufficiently turned, the spring permitting this action, and thus the pad can be more properly located to suit the wearer. This done, the tension of the spring or its pressure is gently upward and backward, or in the natural direction 85 required to crowd the sack back again. Further, the pad, its plate, spring, and pivotal stem are adjustably connected to the end of the metal band. Thus, as shown in Figs. 3, 7, the shank f'' has a projecting pin, f'', fitted to engage in any of the series of holes marked f' in the end of the metal band A. (See, also, Figs. 2, 8.) When the pin f'' engages any of the holes f', the shank or stem F is secured immovably by the screw f'', that joins both the shank 95 and the end of the metal band, as indicated. The pad and its parts thus connected to the metal band can be set at different inclinations, 100 can be raised or lowered, or adjusted to suit

the formation, shape, or curvature of the abdomen.

I have provided another feature of adjustment for purposes of increasing or diminishing the tension of the spiral spring G. It will be noted that to the outside of the shank f² is the face-plate H. This plate H is shown more clearly in Fig. 6, and has the series of holes marked h, also the respective screw-holes h' h².
 10 The same screw f³ that passes through the end of the metal band, also through the shank f², passes through the hole h² of this face-plate. By the farther screw g, passing through the hole h' and engaging only the shank f², the 15 said shank and face-plate H are secured firmly together. g' is the end of the spring, turned upward and adapted to engage any of the holes marked h. When the end of the spring is fastened in the lowest hole, the tension of the 20 spring is increased; when fastened in the middle hole, the tension or pressure is medium, and when fastened in the upper hole the tension of the spring is weakest. By thus being able to increase or diminish the spring-tension 25 the pressure of the pad can be the better suited to the requirements of the hernia complaint.

I show, forming part of the pad, the further projection or button I, which, when the sack has been seated, prevents any receding action 30 and keeps the pad properly located in its place.

My invention is suitable for infants or adults, and can be used single (as here illustrated) or the hernia-truss can be made double by duplicating the same parts with but slight modifications.
 35

What I claim is—

1. In a hernia-truss, the combination of the pad C, secured to the pad-plate D, and the spiral spring G, having one end secured to the sleeve E of said plate, the other end of said spring 40 secured to a stem, F, substantially as and for the purposes set forth.

2. In a hernia-truss, the combination of the face-plate H, having the series of holes h, and the spring G, its end fitted to engage any of 45 said holes, substantially as and for the purposes set forth.

3. In a hernia-truss, the combination of the stem F, consisting of a stem, f, having a threaded portion, f', shank f², and pin at f³, 50 and the spring G, secured over said stem, and by its end g' fitted to engage any of the holes h of a face-plate, H, secured to the shank of said stem, substantially as set forth.

4. In a hernia-truss, in combination with 55 the band A, having holes f⁴, the stem F, its shank f², having pin f³, and secured by screw f⁵ to said band, the face-plate H, having holes h, and secured by screw g to said shank, and the spring G, having one end secured to said 60 stem F, at the same time held in tension with said face-plate, the other end of said spring secured to the sleeve E of a pad-plate, D, carrying the pad, all constructed to operate in the manner and for the purposes set forth. 65

In testimony of said invention I have hereunto set my hand.

FRANZ BREITSCHEID.
